UNITED STATES PATENT OFFICE.

JOHN H. WYMS, OF OAKLAND, CALIFORNIA, ASSIGNOR OF ONE-HALF TO
MAIER A. CAHN, OF SAME PLACE.

GRASS-COLLECTING ATTACHMENT FOR LAWN-MOWERS.

SPECIFICATION forming part of Letters Patent No. 293,208, dated February 5, 1884.

Application filed March 30, 1883. (No model.)

To all whom it may concern:

Be it known that I, JOHN H. WYMS, a citizen of the United States, residing in the city of Oakland, Alameda county, and State of California, have made and invented certain new and useful Improvements in Grass-Collecting Attachments to Lawn-Mowers; and I hereby declare that the following is a full, clear, and exact description of the said invention, reference being had to the accompanying drawings.

My invention relates to grass-collecting receptacles that are provided as part of or as attachments to lawn-mowers, to receive the cuttings; and my improvement in such class of attachments or receptacles, as hereinafter fully described, consists in covering over and inclosing the cutting apparatus, so that the knives or cutters are closed in above, behind, and in front, and all the clippings thrown off by the cutters are caught and collected. For such purpose I provide a rectangular box-shape structure to fit over the frame of the apparatus, above the knives or cutters, in such manner that a receptacle is afforded, both in front of and behind the cutters, to catch and hold the cuttings produced and thrown off from the cutters. These receptacles are removable compartments adapted to be withdrawn from the attachment to remove the cuttings without disturbing the position of the attachment itself. The sides, ends, and top of the attachment are closed to shut off the wind and keep in the cuttings.

The following description fully explains the nature of my said improvement and the manner in which I proceed to construct, apply, and use it, the said drawings being referred to by figures and letters as follows:

Figure 1 represents in perspective a hand lawn-mower with my improved attachment applied to it. Fig. 2 is a view of the attachment removed from the mower. Fig. 3 is a vertical longitudinal section.

A represents a rectangular box-like frame, provided with hinge doors or lids B B in the top, and closed at the sides, but open on the bottom. The open ends are fitted with drawers or removable compartments D D', of which the larger or principal one, D, is placed at the rear and behind the cutters, and the smaller, D', at the front. These compartments have

closed bottoms, sides, and fronts, but are open at the tops and backs. They are arranged to slide in and out, so that they can be readily withdrawn to empty their contents. Suitable fastenings—such as hooks or bolts—are applied on the outsides, to keep them in place within the frame. A space, E, is left between the inner ends of these two drawers of sufficient size to let in the cutters of the machine and allow them to project into the box A. Across the inner end of each drawer is a turned-up ledge, d, to hold in the cuttings that are thrown off the cutters and into these two receptacles by their centrifugal force. The greater part of the cuttings are thrown off at the back of the knives, and therefore the rear receptacle, D, is made considerably larger than the front one. By combining the two with the cutters in this manner a complete retention of the cuttings is insured. As the proportion of cuttings thrown off at the front of the knives is very small, however, this front compartment may be stationary, instead of being removable like the principal receptacle.

The cut-away portions e on the sides fit over the axle just inside the wheels of the machine, and the rear end of the frame or box is attached to the mower-handle H by a hook and eye, C.

The lids or covers B are simply light frames hinged to the sides of the box and covered with wire-cloth b', through which the interior of the box is at all times open to the inspection of the operator, while the cuttings are confined.

This attachment is readily applied to any style of mower with slight alterations in the size of the aperture for the cutters. It does not add materially to the weight of the implement, is readily made at small expense, and it affords a complete device or attachment for gathering the cuttings and keeping them from being thrown upon the surface of the cut grass.

Having thus fully described my invention, what I claim, and desire to secure by Letters Patent, is—

1. The herein-described detachable grass-collecting attachment for lawn-mowers, consisting of the frame A, adapted to fit over and inclose the cutting apparatus of the mower, the removable drawers or compartments D D', the lid or cover B, and means for attaching

the rear end of the frame to the mower-handle, constructed for application and use substantially as set forth.

2. The combination of the box A, having 5 covered top B, and the space E in the bottom to receive the cutters of a lawn-mower, the front receptacle, D', and the rear receptacle, D, adapted to be withdrawn from the box to discharge its contents and clean out the 10 receptacles, substantially as and for the purpose set forth.

3. A detachable grass - collecting box for lawn-mowers, having the drawers D D' in front and rear of the mower, covered sides, and hinged top, provided with the wire-cloth portions b', 15 substantially as set forth.
